United States Patent Office

Des. 223,918

Patented June 20, 1972

223,918

ELECTRIC HEATER HOUSING

Geoffrey T. Gray, Lambertville, Mich., assignor to
Eprad Incorporated, Toledo, Ohio

Filed Jan. 15, 1971, Ser. No. 106,947

Term of patent 14 years

Int. Cl. D23—03

U.S. Cl. D23—123

FIG-3-

FIG-2-

FIG-1-

FIG. 4 -

FIG. 5 -

FIG. 6

FIG. 1 is a perspective view of an electric heater housing embodying my new design;

FIG. 2 is a front elevational view thereof on an enlarged scale;

FIG. 3 is a rear elevational view thereof on an enlarged scale;

FIG. 4 is a top plan view thereof;

FIG. 5 is a side elevational view thereof;

FIG. 6 is a bottom plan view thereof.

I claim:

The ornamental design for an electric heater housing, as shown and described.
